UNITED STATES PATENT OFFICE.

DAVID W. LANDES, OF BOISE, IDAHO, ASSIGNOR OF ONE-HALF TO FLORA E. LANDES, OF BOISE, IDAHO, AND ONE-HALF TO ELMER E. SIMS, OF MERIDIAN, IDAHO.

GUN-CLEANER.

No. 876,276.

Specification of Letters Patent.

Patented Jan. 7, 1908.

Application filed May 6, 1907. Serial No. 872,170.

To all whom it may concern:

Be it known that I, DAVID W. LANDES, a citizen of the United States, residing at Boise, in the county of Ada and State of Idaho, have 5 invented a new and useful Gun-Cleaner, of which the following is a specification.

This invention has reference to improvements in gun cleaners, and its object is to produce a gun cleaner which, after being 10 inserted in the barrel of a gun, may be given any desired degree of expansion therein and may then be rotated or moved longitudinally in the gun barrel without danger of changing the adjustment already established.

15 The invention consists essentially in a threaded stem provided with an expansion nut, said stem being rotatable in a suitable base carrying a number of flexible fingers terminating in cleaning-pads. The relation 20 of the fingers to the nut is such that when the nut is moved on the threaded stem in one direction the fingers are allowed by their resiliency to approach each other, while when the nut is moved in the other 25 direction on the stem the fingers are expanded against the action of their resiliency. In order to turn the threaded stem to cause the nut to move thereon, the nut being held by the fingers from rotation, the cleaner rod 30 carries at its end a rotatable sleeve fast for rotation to the threaded stem and movable longitudinally thereon, while the supporting member for the fingers is provided with bayonet slots or equivalent means whereby 35 the sleeve and stem may be locked to the finger carrier so that the entire cleaner head may be rotated within the gun barrel or moved longitudinally therein without danger of disturbing the relation of the nut and 40 fingers in any manner.

The invention will be fully understood from the following detailed description, taken in connection with the accompanying drawings forming part of this specification, 45 in which,—

Figure 1 is a side view of the improved cleaner head, drawn on a somewhat enlarged scale, and also showing a portion of the cleaner rod; Fig. 2 is a longitudinal section 50 of the structure shown in Fig. 1; Fig. 3 is a similar section of the base portion of the structure shown in Figs. 1 and 2, in a different phase of its operation; and Figs. 4 and 5 are detail views of the finger-carrying portion of the cleaner.

Referring to the drawings, there is shown a threaded stem 1 upon which is mounted a nut 2 of general tetrahedral form such as is commonly used in gun cleaners and in other relations where an expansion nut is desired. 60 The stem 1 passes centrally through a cylindrical block 3, which latter has undercut grooves formed in it for the reception of cleaner blades 4 fast to its periphery by screws 5. The cleaner blades carry at their 65 outer ends suitable pads 6 of wire gauze or some such material, and on their inner faces are provided with guide frames 7 fast to the ends of the blades and so shaped as to coat with the nut 2. These blades have a normal 70 tendency to approach the stem 1 so that when the nut is screwed toward the end of the stem the blades will approach the stem and thus be adapted to easily enter the bore of the gun. But when the nut is screwed 75 toward the other end of the stem it engages the ends of these blades with a constantly increasing diameter and therefore causes them to spread outwardly. This brings the pads to bear with any desired force upon the inside 80 walls of the gun barrel, and by twisting and moving the cleaner head back and forth every part of the gun barrel may be reached and treated by the cleaner head with any desired degree of force. 85

The screws 5 which hold the blades 4 are long enough to enter the bore of the block 3 and extend into an annular groove 8 in the stem 1, so that the latter, while freely rotatable within the block 3, cannot be moved 90 longitudinally with reference thereto. To the rear of the annular groove 8 the stem 1 is provided with a longitudinal through slot 9 and ultimately terminates in a reduced stem 14. 95

The block 3 is provided at its rear side with a reduced neck 11 in the rear end of which are formed 2 longitudinal slots 12 having a right angle extension 13 at one end after the manner of an ordinary bayonet catch. Fitted to the neck 11 there is a sleeve 14 through which passes a pin 15 extending diametrically through the walls of the sleeve 14 and through the slot 9 in the stem 1. This pin is also adapted to the longitudinal slots 12 in 105 the neck 11 and may be moved longitudinally on said neck until the sleeve meets the body of the block 3 when by rotating the sleeve 14 on the neck 11 the pin 15 will enter the angle extensions 13 of the slots 12, thus locking 110

this sleeve firmly in place and at the same time locking the stem 1 against rotation. When, however, the sleeve is pulled away from the block 3 to the full length of the slot 9 5 the pin 15 is beyond the end of the neck 11 although the sleeve still remains on the said neck. When in this position the sleeve may be freely rotated upon the neck and carry the stem 1 with it. This will cause the nut 2 to 10 travel in one direction or the other on the sleeve since this nut is held from rotation by the engagement of the free ends of the cleaner blades 4.

The sleeve 14 is provided with an axial 15 passage for the reception of the reduced portion 10 of the stem 1, and the sleeve 14 is also provided with a threaded neck 16 for the reception of a threaded socket 17 formed on the end of the cleaner rod 18, which latter, of 20 course, may be of any length desired.

It will now be seen that the cleaner may be introduced into a gun barrel in the contracted condition and after being introduced the nut may be caused to travel toward the block 25 3 by rotating the sleeve 14 when in a position to have the pin 15 back of the neck 11. This will cause the expansion of the pads 6 against the inside walls of the gun barrel with any force desired, after which the sleeve 14 may 30 be pushed to carry the pin 15 into the slots 12 and by a turn of the sleeve the latter may be locked in the extensions 13 of these slots. When so locked, the cleaner head may be rotated and moved longitudinally in the gun 35 barrel in either direction without danger of changing the diameter of the cleaner head or affecting it in any way, and the cleaner head may be tightened or loosened by simply reversing the direction of rotation and pulling 40 the cleaner rod 18 toward the operator, when the sleeve 14 with the stem 1 may be rotated in either direction.

I claim:—

1. A gun cleaner comprising an expandible and contractile cleaner head means 45 for causing the expansion and contraction of the cleaner head, a rotatable member carried by the cleaner rod, and a lock for coupling the rotatable member to the cleaner head 50 and at the same time locking the means for

causing the expansion and contraction of the said cleaner head.

2. A gun cleaner comprising a rotatable, threaded stem, a block to which said stem is fixed except against rotation, a nut carried 55 by said stem, cleaner blades mounted on said block and coacting with said nut, means for rotating the stem, and a lock for fixing the stem-rotating means and the stem against rotation in the block carrying the cleaner 60 blades.

3. A gun cleaner comprising a rotatable, threaded stem, a nut carried thereby, cleaner blades in operative relation to the nut, a block carrying said cleaner blades and holding said stem against longitudinal movement but permitting its rotation, a reduced neck formed on said block and provided with bayonet catch grooves, a sleeve fitting said neck and movable longitudinally thereon, 65 and a pin passing through said sleeve and through a slot in the threaded stem and adapted to be moved with said sleeve longitudinally with relation to said stem into and out of the slots in the neck of the block. 70

4. A gun cleaner comprising a threaded stem provided with an annular groove and with a longitudinal slot, a nut carried by the threaded portion of the stem, cleaner blades provided with cleaner pads and in operative 80 relation to said nut, a block carrying said cleaner blades and having means entering the annular groove in the stem to hold the same against longitudinal movement with relation to the block, a reduced neck formed 85 on said block and provided with angle slots, a sleeve adapted to said neck and having a reduced portion to receive a cleaner rod, and a pin passing diametrically through the sleeve and through the slot in the stem and 90 movable longitudinally with relation to the stem to enter the angle slots formed in the neck of the block.

In testimony that I claim the foregoing as my own, I have hereto affixed my signature 95 in the presence of two witnesses.

DAVID W. LANDES.
